[57] CLAIM

I claim the ornamental design for wedding gown bustle looper, as shown and described.

DESCRIPTION

FIG. 1 is a front perspective view of a wedding gown bustle looper showing my new design;

FIG. 2 is a front elevation view thereof, the rear elevation being a mirror image;

FIG. 3 is a top plan view thereof, the bottom plan view is essentially the same;

FIG. 4 is a left end elevational view thereof; and,

FIG. 5 is a right end elevational view thereof.
